UNITED STATES PATENT OFFICE.

HENRY ZENAS COBB, OF WINCHESTER, MASSACHUSETTS.

BRAIDING-MACHINE.

1,133,364.

Specification of Letters Patent. Patented Mar. 30, 1915.

Application filed January 31, 1913. Serial No. 745,361.

To all whom it may concern:

Be it known that I, HENRY ZENAS COBB, a citizen of the United States, residing in Winchester, in the county of Middlesex and 5 State of Massachusetts, have invented certain new and useful Improvements in Braiding-Machines, of which the following is a specification.

This invention relates to braiding machines, and in particular to machines for braiding tubular fabrics.

My present invention is applicable to any ordinary braiding machine, preferably to one designed for braiding tubular fabrics 15 and preferably one having two concentric raceways, in order to simultaneously braid two or more webs.

My present invention provides a supplemental mechanism or attachment whereby 20 to introduce any desired number of longitudinal warp yarns into the braided fabric. For this purpose I provide as many shuttles as there are yarns to be introduced, these shuttles being normally located beneath the 25 shed of interbraiding yarns, and being projected upwardly through the shed by shuttle-throwing devices of novel construction.

Each shuttle travels in a vertically extended shuttle raceway made in two sections and 30 having a gap between them for the passage of the shed of braiding yarns. For controlling the shed it is confined between two rings located respectively above and beneath the shed, the space between them forming the gap in which the braiding yarns travel. 35 The approaching surfaces of these rings are preferably made sinuous, these edges drawing closer together in the paths of the shuttles and diverging between such paths.

40 Referring to the accompanying drawings which show the preferred embodiment of the invention, Figure 1 is a vertical mid-section of so much of the braiding machine as is necessary to show the application of 45 my invention. Fig. 2 is a fragmentary sectional elevation showing one of the shuttle races and the shuttle-throwing means.

In the machine shown *a a* are the bobbins 50 which travel in a raceway *A* in the usual manner, the raceway having any suitable number of bobbin slots or tracks so as to braid one, two or more plies. The yarns *b b* from the bobbins pass in the usual manner to a central core *B*, where the yarns braid together 55 to form the tubular braided fabric *C*. The converging yarns *b b*, being fed off by bob-

bins traveling partly in right-hand and partly in left-hand direction, are in two series respectively crossing one another, the yarns of both series constituting what is 60 herein called the shed. This shed of yarns is best arranged in an obtusely conical order as shown, the yarns of the shed playing between upper and lower guide rings *D D'* 65 fixedly supported from the frame of the machine. The gap *d* between these rings is wide enough to permit the free play of the yarns of the shed while preventing their displacement in vertical direction during the passage of the shuttles.

70 The shuttles *E E* are mounted to travel in separate upright raceways or shuttle races *F F'*, the lower races *F* being separated from the upper races *F'* by a distance corresponding to the gap *d*, so that the 75 yarns of the shed may freely play between them. As many shuttles and races are provided as equals the number of longitudinal yarns that it is desired to incorporate in the braided fabric. Two shuttles are shown 80 in Fig. 1, the one at the left being down and the one at the right being up. The 85 yarns *e*, paid off by the shuttles, join the braiding yarns at their convergence where they unite to form the braided web.

85 The shuttles which normally occupy their position beneath the web, are thrown upwardly by the shuttle-throwing means to be described and when their momentum is expended they fall back, descending through 90 the web. Each shuttle has a shuttle-throwing slide or plunger *G* beneath it sliding in the shuttle-race *F* or in any equivalent guide alined therewith. For elevating these slides in the proper succession a cam wheel *H* is 95 provided, mounted preferably in a horizontal plane and concentric with respect to the braiding machine. It is shown as having gear teeth *f* on its under side meshing with a pinion *g* on a driving shaft *h*. The wheel 100 *H* has a suitable projection *i* near its rim which constitutes the operating part, by the action of which the shuttles are thrown in succession. In the preferred construction shown this projection *i* has a flat upper face 105

serving as a frictional or tractor surface which engages in turn a series of friction wheels or rollers *I I* which are preferably faced with leather, rubber or other frictional facing, so that as the projection *i* passes beneath them successively it sets them in rotation. These friction rollers are connected in 110

any suitable way to the respective slides G so that their rotation imparts a lifting movement to the slides. In the preferred construction shown each roller I is mounted on a shaft and has connected to it a wheel or drum J, to which is connected a belt or strap j, which passes up and over an idler pulley k and thence down, and is attached to the lower part of the corresponding slide G. The parts are normally in the position shown at the left in Fig. 1, the weight of the slide holding the parts in this position. When the projection i encounters the friction roller I it sets it in rotation so that the drum J winds the strap j around it, thereby exerting a pull through this strap which is communicated to the slide G and throws this slide forcibly upward. The frictional face of the projection i is only sufficiently long to certainly accomplish this movement. When the projection i passes beyond the roller the weight of the slide G causes it to descend, thus pulling the strap and unwinding it, and restoring the parts to their first position. This operation is performed upon one after the other of the shuttle-throwing mechanisms. As each slide is thrown up it throws the shuttle E through the shed and to any desired distance above it, according to the time that it is desired shall elapse before the shuttle falls and again passes through the shed. During this interval the yarns b of the shed are advancing so that when the shuttle descends it carries its yarn through the shed between different yarns thereof from those parted by the shuttle when ascending. Each slide G at the upper limit of its travel is stopped by a buffer or cushion which stops it yieldingly and starts it on its return movement. In the construction shown the slide has a projection l which strikes a rubber cushion m. The moment that this projection strikes the buffer the friction roller has run off the surface of the projection i, thus leaving the slide free to fall back so that it descends before the shuttle in its descent can overtake it. The wheel H is driven sufficiently fast so that it imparts a quick forcible upward throw to each of the slides G whereby the latter throws the shuttle through the braiding yarns and carries it preferably several inches above the shed, so as to allow ample time for the travel of the braiding yarns be-

fore it returns, and so that the shuttle in descending acquires considerable velocity before again entering the shed, so that it passes through the latter as quickly as practicable. It is preferable to have only one cam projection or traction face i on the wheel H and to drive this fast enough so that each shuttle is thrown upward quickly while yet abundant time is allowed for the descent of the shuttle-throwing slides and the shuttle. The slide falls considerably in advance of the shuttle and remains down until the descending shuttle strikes it. To relieve this blow and diminish the sound the slide carries a rubber bumper, shown at p, in Fig. 2. Any suitable framework is provided for supporting the respective mechanical parts. The gap d between the rings D D' is of varying width, the approaching edges of the rings being sinuous so that they approach each other and narrow the gap coincidently with the shuttle races and recede from each other to widen the gap between such races.

The mechanism described is subject to considerable modification and to the substitution of equivalent mechanical devices or elements without departing from the invention.

What I claim is:—

1. In a braiding machine, guide rings between which the yarns forming the braiding shed travel, a shuttle movable through said shed adjacent to said rings, and means for throwing the shuttle, said rings approaching each other adjacent to the path of said shuttle whereby to narrow the shed where the shuttle penetrates it.

2. In a braiding machine, guide rings between which the yarns forming the braiding shed travel, a shuttle raceway adapted to guide a shuttle through the shed adjacent to said rings, and means for throwing the shuttle, said guide rings approaching each other adjacent to said raceway to narrow the shed where the shuttle penetrates it.

In witness whereof, I have hereunto signed my name in the presence of two subscribing witnesses.

HENRY ZENAS COBB.
